UNITED STATES PATENT OFFICE.

EUGENE FRANK SCHOELL, OF NEW BRITAIN, CONNECTICUT.

CURTAIN-FASTENER.

1,322,141.

Specification of Letters Patent.

Patented Nov. 18, 1919.

Application filed April 14, 1919. Serial No. 289,842.

To all whom it may concern:

Be it known that I, EUGENE FRANK SCHOELL, a citizen of the United States, residing at New Britain, in the county of Hartford and State of Connecticut, have invented certain new and useful Improvements in Curtain-Fasteners, of which the following is a specification.

The object of this invention is to promote the serviceableness and efficiency of curtain fasteners of the spring-type illustrated in the invention of my case Serial No. 168,194, filed May 12, 1917, (Patent No. 1,312,158, dated August 5, 1919.)

15 The invention consists of a resilient stud member made in one piece of spring metal and having a confined attaching base whose ends are returned over and free of the base and are resilient and carry the socket-engaging spring active parts or arms, as I will proceed now to explain and finally claim.

20 In the accompanying drawings illustrating the invention, in the several figures of which like parts are similarly designated, Figure 1 is a plan view of my improved curtain fastener and part of a curtain held in place thereby. Fig. 2 is a plan view of the curtain fastener without the curtain.

25 Fig. 3 is a plan view of the socket member. Fig. 4 is a plan view of the stud member. Fig. 5 is a plan view of the blank for the stud member. Fig. 6 is a sectional view on a larger scale taken on the line 6—6 of Fig.

30 1. Fig. 7 is a view similar to Fig. 6 with the parts in position for disengagement. Fig. 8 is a bottom view of the socket member, and part of curtain, being in part broken away.

35 40 My improved curtain fastener comprises a socket member 10 adapted to be secured to the curtain 11 and a stud member 12 adapted to be secured to the woodwork, and these two members resemble and also differ from the socket member and the stud member respectively shown and described in the application mentioned, in the particulars hereinafter mentioned among others.

In the case of the socket member 10, the opening or hole 14 therein for engaging with the head of the stud member is of circular form instead of the non-circular form shown in the earlier case. Any approved manner of securing the socket member 10 to the curtain 11 may be employed. In the instance shown, there is a washer-like body 16

adapted to be positioned against one face of the curtain 11 and having a neck 17 that forms the border wall of the stud-engaging hole 14 and projects through the curtain 11, 60 its outer end portion 19 being headed over against the outer face of a washer 20 that is positioned against the opposite face of the curtain 11.

The parts of the stud member 12 that 65 compose the head 21 for coöperating with the stud-engaging hole 14 in the socket-member 10 differ in details as to shape from the form shown in the earlier case to correspond to the change in shape of the socket 70 opening or hole 14 referred to.

The stud head parts comprise two similar and mating arms 22 that are positioned normally generally in parallelism and in spaced relation, and extend outwardly from 75 the base structure of the said member 12, and each has on its outer face an overhanging rigid tooth or lug 23 that is adapted to engage with the border portion of the opening 14 to effect the engagement of the socket 80 and stud.

The overhanging lug 23 is formed by forcing outwardly the part of the material of the arm 22 that is just above a relatively short cross-slit 24 in the said material, substantially as in the case of the form shown 85 in the earlier case.

Thus, as described, one special feature of the present device is the circular form of the opening 14 in the socket member 10, and 90 another special feature is the construction and arrangement of the parts of the stud member 12, which latter will now be described.

As in the earlier case, the stud member 95 12 is formed of a single piece of strip sheet material, the end portions of which serve as the arms 22. The middle portion 25 of the said strip is straight and flat, of appreciable length, extends across the lower ends of the 100 arms 22, rests on the woodwork or other support 13, and has a pair of holes 26 for the screws 27 by which it is secured to the said support 13 so as to serve as the base for the said stud member 12.

The stud member 12 is a symmetrical structure, as shown, and the screw holes 26 are positioned in spaced relation, equidistant from the middle or the transverse axial line.

The base 25, therefore, comprises a central 110 part 28 that is confined between the holding screws 27 and end parts 29 extending out-

wardly from the ends of the said confined part 28 to the outer ends of the base 25, corresponding to the position of the folding lines 30 shown in the view of the blank in 5 Fig. 5.

The said end parts 29 are unconfined and free and are therefore adapted to act and do act in each case as parts of the spring members, which spring members comprise on 10 each side all of the material outward from the end of the confined portion or part 28. Thus the inactive part is limited to confined part 28, as determined by the screw holes 26, and all of the rest of the material 15 of the blank is free, so that the resiliency thereof may be utilized in effecting engagement with the socket member and disengagement therefrom. The portions 31 overlying the base are connected to the outer unconfined end parts 29 of the base 25 by the return bends 32 which are positioned substantially along the folding line 30, already mentioned, and these portions 31 are connected to the lower ends of the arms 22 by 20 the bends 33 which are approximately right angles and the position of which is indicated by the folding line 34 in the view of the blank in Fig. 5.

The connecting portions 31 have holes 35 30 registering with the holes 26 in the base and larger than the said holes 26 so as to provide clearance for admitting the heads of the screws 27 for engaging with the base 25 and to avoid such engagement by the said 35 screw-heads with the intermediate or connecting portions 31 as would interfere with the free spring movement thereof.

I prefer to have the bend 32 in the form of a U-shape of small curvature, as distinct 40 from a sharp return bend, and also to have the parts constructed and arranged so that the connecting parts 31 are normally positioned in spaced relation to the base 25 generally, being separated therefrom by the 45 spaces 36, so as to permit freedom of movement of the spring member or spring unit as a whole. These spaces 36 are particularly advantageous in effecting disengagement of the socket member 10 and the stud 21, which 50 disengagement is effected by springing together the arms 22. Thus, in effecting such disengagement the entire composite spring member or spring unit, as described, at each 55 end of the confined part 28, is active as a spring device.

As shown, the base 25 is secured to the woodwork or other support by means of two

screws and these are symmetrically arranged. In some cases some other means of support may be used without affecting the 60 operation, other than in degree. Thus in some cases a single supporting or holding screw may be used and this may be positioned precisely at the middle of the structure. 65

The advantage of the circular form of the stud-engaging opening or hole 14 lies in the fact that there is avoided a definite positioning of the part for effecting engagement, such as is necessary with a non-circular 70 form of opening.

I claim as my invention:—

1. A curtain fastener, comprising in combination a socket member having an opening of circular form and a stud member having 75 a confined base and overlying spring elements spaced apart from said base, and a head portion in the form of a pair of arms extending outwardly from said spring elements in spaced relation to each other and 80 having externally projecting rigid holding lugs on their outer faces, the said head portion being constructed and arranged so that when positioned in the said opening 85 the said lugs will overhang and engage with the border wall of the said opening.

2. A stud member formed of a single piece of strip sheet material, comprising a confined part at the middle that serves as an inactive part and a pair of active parts positioned one on each side of the said confined part, said active parts comprising each an arm that serves as part of a stud structure and a portion in the form of a return bend interconnecting the said arm and one end of 95 the said confined part, and externally projecting rigid lugs on said arms. 90

3. A stud member formed of a single piece of strip sheet material, comprising a confined part at the middle that serves as an inactive part and a pair of active parts positioned one on each side of the said confined part, said active parts comprising each an arm that serves as part of a stud structure and a portion in the form of a return bend 100 interconnecting the said arm and one end of the said confined part, said confined part having a hole adjacent to each of the junctions of the said confined part and active parts to receive holding screws, the active 105 parts having clearance holes for the heads of such holding screws. 110

EUGENE FRANK SCHOELL.

It is hereby certified that in Letters Patent No. 1,322,141, granted November 18, 1919, upon the application of Eugene Frank Schoell, of New Britain, Connecticut, for an improvement in "Curtain-Fasteners," an error appears in the printed specification requiring correction as follows: Page 1, line 13, for the Patent No. "1,312,158" read 1,312,138; and that the said Letters Patent should be read with this correction therein that the same may conform to the record of the case in the Patent Office.

Signed and sealed this 2d day of December, A. D., 1919.

[SEAL.]

M. H. COULSTON,

Acting Commissioner of Patents.
